CLAIM

The ornamental design for a light-emitting diode package, as
shown and described.

DESCRIPTION

FIG. 1 is a top perspective view of a light-emitting diode
package;

FIG. 2 is a bottom perspective view of the light-emitting
diode package of FIG. 1;

FIG. 3 is a top view of the light-emitting diode package of
FIG. 1;

FIG. 4 is a bottom view of the light-emitting diode package of
FIG. 1;

FIG. 5 is an end view of the light-emitting diode package of
FIG. 1;

FIG. 6 is an opposing end view of the light-emitting diode
package of FIG. 1;

FIG. 7 is a side view of the light-emitting diode package of
FIG. 1; and,

FIG. 8 is an opposing side view of the light-emitting diode
package of FIG. 1.

The dashed broken lines shown in the drawings depict
portions of the light-emitting diode package that form no
part of the claimed design.

The dot-dashed broken lines shown in the drawings depict
portions of the light-emitting diode package that represent
boundaries of the claimed design and are not part of the
claimed design.
